OIL LANTERN CONSTRUCTION

Alfred J. Perkins, Warsaw, N. Y., assignor to
Embury Manufacturing Co., Warsaw, N. Y., a
corporation of New York

Application April 12, 1934, Serial No. 720,254

3 Claims. (Cl. 240—50)

This invention relates to oil lantern constructions and has for one of its objects to provide an improved form of air intake and air chamber surrounding the burner of the lantern which 5 are so arranged that the force of even extremely strong winds and air currents cannot penetrate to the burner flame and blow it out.

Another object of this invention is to provide 10 the lantern with a novel form of globe seat surrounding the burner which keeps strong air currents from entering at the bottom of the globe.

A further object of this invention is to surround 15 the lantern globe with a guard which is mounted on top of a large font and supports the dome of the lantern directly from the font.

All these and other objects and advantages of 20 this invention will become more readily apparent from the detailed description thereof which follows, reference being had to the accompanying drawing in which—

Figure 1 is a partial side elevation and vertical 25 sectional view of the novel lantern construction.

Figure 2 is a horizontal sectional view of the 30 lantern without the globe the section being taken on the line 2x—2x of Figure 1 looking down onto the font of the lantern.

Figure 3 is a horizontal sectional view of the 35 lantern without the globe and taken on the line 3x—3x of Figure 1 looking up to the dome of the lantern.

In the several figures of the drawing like reference numerals indicate like parts.

The novel lantern construction forming the 40 subject matter of this invention comprises a large cylindrical font 1 which is reinforced at the bottom around the outer edge by the wire 45 loop 2. A cylindrical partition 3 is held centrally of the font by the cover 4. On top of the font is provided the air chamber 5 which has an inclined outer wall 6, a substantially flat bottom 7 forming part of the cover of the font and a vertical cylindrical inner wall 8. At the top of this air chamber between the top of the outer 50 inclined wall and the top of the cylindrical vertical wall is provided the annular channel seat 9 into which the bottom flange 10 of the lantern globe 11 is adapted to telescope and seat itself 55 therein. As will be seen from an inspection of the sectional portion of the air chamber 5, the inner wall of the annular channel seat 9 is higher than the outer wall thereof over which the globe projects in order to completely seal the flange 10 of the globe into the annular seat and prevent

the admission of air into the globe at the bottom thereof.

The cylindrical inner wall 8 of the air chamber 5 forms a well 12 in which the lantern burner 13 is mounted. The air intake for the air chamber 5 is provided by two rows of small openings 14 and 15 arranged circumferentially near the top of the inclined outer wall 6 thereof. The upper row of openings 14 is preferably located in front of the annular channel seat 9 so that the air 10 entering these openings is deflected downwardly into the chamber 5 and deflects with it the air entering the lower row of openings 15. In this way the air entering the air chamber 5 is baffled and cannot immediately enter the burner well 12 thru the outlets 16. Therefore no matter how strong the current of air is which enters the air chamber, the force of it is greatly diminished before the air leaves the chamber thru the outlet openings 16 in the inner wall 8 and enters the well 12 of the burner. The oxygen for the combustion of the oil is thus supplied by an air current which at no time is strong enough to cause the flame of the burner to be blown out thereby.

This is further helped by the outer inclined 25 wall 6 in which the air inlet openings are located. This inclined wall causes the air currents to strike the openings 14 and 15 at an angle which deflects part of the air current past the openings and keeps the full force of the air currents 30 from entering the air chamber 5.

The guard, surrounding the lantern globe 11, is made up of a series of vertical rod members 17 which are bent outwardly at the bottom to nest 35 into the depressions 18 and are welded or soldered thereinto. At the top the vertical rod members are provided with suitable eyes to support the horizontal top member 19 of the guard. At a point substantially in the middle, the vertical rod members are surrounded by the circular 40 wire member 20 which is suitably soldered or welded thereto.

As illustrated in Figure 3 the horizontal top member 19 of the guard has integrally formed thereon at diametrically opposite points the outwardly and upwardly projecting ears 21 and 22 which support the bale 23 of the lantern between them. The horizontal top member 19 of the guard is also offset between two of the vertical rod members as indicated at 24 and to this offset portion is hinged the dome 25 so as to swing 50 thereon.

Within the dome 25 is yieldingly suspended the cap 26 which telescopes over the top of the globe 11. Air enters this cap thru the openings 55

27 and is deflected upwardly therein by the inclined baffles 28. The air thus entering at the top of the globe creates an up draft which helps to carry off the products of combustion from the 5 burner flame thru the openings 29 in the top of the cap into the upper portion of the dome and thru the openings 30 in the dome to the outside of the lantern.

I claim:

- 10 1. In an oil lantern having a font, the combination of a burner well located on top of the font centrally thereof and open at the top and closed at the bottom, an air chamber surrounding said burner well and having a closed top and bottom, an inclined wall on the outside of said air chamber having inlet openings therein, a wall separating said air chamber from said burner well and having outlet openings therein substantially opposite to said inlet openings and leading from said air chamber into said well.
- 15 2. The construction in an oil lantern as set forth in claim 1 with an annular channel seat

provided on top of said air chamber so as to have its sides and bottom extend into said air chamber between its inlet and outlet openings in the outer and inner wall thereof.

3. In an oil lantern having a font, the combination of a burner well located on top of the font centrally thereof and open at the top, an air chamber surrounding said well and having a closed top and bottom, an inclined wall on the outside of said air chamber having inlet openings therein, a wall separating said chamber from said burner well and having outlet openings therein leading from said air chamber into said well, an annular channel seat provided in the top of said air chamber and extending thereinto between its inlet and outlet openings with the outside wall of said annular channel providing a baffle for the air entering the intake openings in the inclined outer wall of the air chamber.

ALFRED J. PERKINS.
